EXTENSIBLE GASOLINE DISPENSING HOSE
AND ASSOCIATED MECHANISM

H. Hix Wolfe, Dayton, Ohio, assignor to The Dayton Pump and Mfg. Company, Dayton, Ohio, a corporation of Ohio

Application December 5, 1947, Serial No. 789,896

3 Claims. (Cl. 299—78)

1

The present invention relates to a dispensing hose and is concerned primarily with a hose designed for use in conjunction with a gasoline dispensing pump.

When an automobile drives up to a gasoline pump, the range in which the automobile may park is limited by the length of the dispensing hose. If this hose is long, the car may be parked in an accessible position over a fairly wide range. On the other hand, if the hose is short, this range is materially limited. In accordance with well accepted practice, one end of a gasoline hose is connected to the pump adjacent to the top thereof while the other end carries a discharge nozzle. This discharge nozzle is intended to be received in a support which is also adjacent to the top of the pump when the nozzle is not in use. To the end of eliminating any snarling or entanglements in the hose, it has been the practice to limit these hoses in length to a degree corresponding to the height of the pumps, that is, the bend of the hose between the fixed connection and the nozzle is located substantially adjacent to the ground.

Heretofore, the gasoline pumps commonly installed around service stations, garages, and the like have been fairly high with the result that a dispensing hose which is susceptible of support thereby in the manner above indicated is reasonably long and affords the required range in which the car may be parked.

However, in accordance with certain recent trends in the gasoline pump industry, there has developed the practice of installing pumps that are materially shorter in height. Following the old known methods of supporting the hose in position when not in use, this has resulted in materially reducing the range in which a car may be parked with respect to any particular pump and still be in accessible position to have its gasoline tank filled.

With the foregoing conditions in mind, this invention has in view as its foremost objective the provision of a gasoline pump including a hose that is extensible. In carrying out this idea, the invention proposes to follow the old practice of having that part of the hose which is located exteriorly of the pump supported in a suspended position defined by a single bight or bend.

Another important object of the invention is the provision of a gasoline pump together with a dispensing hose with the pump being provided with means for taking up a portion of the extent of the hose therewithin.

Still more in detail, the invention has as an object the provision of a gasoline pump including a sheave which is adapted to have taken up there-

2

on a portion of a gasoline dispensing hose. This sheave is mounted in the upper portion of the pump in a position in which it readily receives the hose and is provided with yieldable means normally retaining the hose in its wound-in or taken-up position.

In providing a pump and hose assembly in accordance with the above noted thoughts, it becomes important to provide for an effective conducting connection between the pumping mechanism proper and the end of the hose which is taken up on the sheave. From the very nature of its operation, the sheave is rotatable and this connection must accommodate this rotation. Accordingly, another highly important object of the invention is the provision of a gasoline pump including a rotatable sheave that is adapted to receive a hose together with conducting connections through the mounting of said sheave to the end of the hose which is received thereon.

In extending the hose into useful position and retracting it into its wound-up state, it is important that the hose be accurately guided so as to prevent snarling. With this thought in mind, a further object of the invention is the provision of a gasoline pump which includes a dispensing hose of the extensible type as above indicated, together with means for guiding the hose as it is pulled out or retracted. This means preferably takes the form of rollers that are suitably arranged and which engage the hose with a guiding action.

Another highly important object of the invention is the provision of suitable retaining means for assuring that the hose remains in proper position on the sheave within the pump.

Various other more detailed objects and advantages of the invention such as arise in connection with carrying out the above noted ideas in a practical embodiment will in part become apparent and in part be hereinafter stated as the description of the invention proceeds.

The invention therefore comprises a gasoline dispensing pump that is provided at the top portion with a sheave on which a portion of a dispensing hose is taken up. Mechanism is provided for guiding the hose and retaining it in position on the sheave together with means for normally retaining the sheave in a wound-up or hose-retracted position.

For a full or more complete understanding of the invention, reference may be had to the following description and accompanying drawings wherein:

55 Figure 1 is a perspective view of a gasoline pump with a car positioned sufficiently close

thereto to have a gasoline tank filled thereby. This view brings out the importance of having the hose extensible.

Figure 2 is a view in side elevation of the pump shown in Figure 1 on an enlarged scale.

Figure 3 is a view in end elevation of the pump shown in Figure 2 with a part of the bottom broken away.

Figure 4 is a top plan view with a portion of the pump casing at the top broken away. This view develops the take-up sheave and brings out the manner in which the hose is wound thereon.

Figure 5 is a view taken normal to the showing of Figure 4 of the upper portion of the pump with the casing broken away to bring out details of the take-up mechanism.

Figure 6 is an enlarged detailed view taken as a vertical section through the hub portion of the take-up sheave and associated mechanism.

Figure 7 is an enlarged detailed view bringing out the connection of the hose to the sheave hub.

Referring now more particularly to Figure 1, a gasoline pump is illustrated therein and is identified in its entirety by the reference character P. This pump P is preferably of the new type in that it is not very high. Thus its top 10 is located fairly close to the base 11 at the ground. An automobile is represented at A and is shown as including a gas inlet at 12. A dispensing hose H has a nozzle at 13 which must be fitted in the inlet 12 when the gasoline tank of the car A is to be filled. The other end of the hose H enters the pump at the point indicated at 14. It is evident that if the driver of the car A is to have fairly wide latitude as to where he may park the car with respect to the pump P and still leave the inlet 12 in an accessible position, the hose H must be fairly long in extent. In fact, it must be longer than would be the case if its length were limited by the height of the pump P.

As shown clearly in Figure 3, the pump casing includes a recess at 15 that defines a notch or support for receiving the nozzle 13 when the latter is not in use. Ordinarily, the length of the hose H would be determined by the position of the points 14 and 15 and the height of the pump P.

The pump P includes a casing which is referred to generally by the reference character C. Enclosed within this casing C is a supporting structure that includes uprights 16 and horizontally disposed cross bars 17 which support a table or cross plate 18.

Referring now more particularly to Figure 6, the table 18 is shown as carrying a base or pedestal 19 which may be anchored thereto in any preferred manner such as by the headed bolts shown at 20. This pedestal 19 is formed with a central recess 21 with which communicates a passageway 22 that extends to one element of a coupling 23. A conduit 24 is also connected to this coupling and extends to the pump mechanism proper which supplies gasoline under pressure to the line 24. Extending upwardly from the pedestal 19 is a tubular column 25 that is closed at its upper end as indicated at 26. Intermediate its extremities the tubular column 25 is formed with a plurality of ports 27.

A hub assembly is mounted on the tubular column 25 for rotation thereabout. This hub is referred to generally by the reference character X and is intended to constitute the hub of a sheave as will be later described. This hub X comprises three main parts, a lower end plate 28, an upper end plate 29, and an intermediate ring 30. The lower end plate 28 comprises a flat ring-like portion having an inner thickened part 31 and an

outer peripheral portion 32 which is somewhat thinner. The inner thickened portion 31 carries a cylindrical wall 33 that is spaced from the tubular column 25. An oil seal designated 34, together with a bearing assembly 35, is mounted in the recess defined by the base 19, column 25, thickened part 31, and cylindrical wall 33. A packing ring 36 is interposed between the thickened portion 31 and the column 25. Immediately above the ring 36 there is a packing gland 37 which carries a sealing ring 38 which is engaged by a spring 39. Another spring 40 is disposed outside of the ring 39 and engages the packing gland 37.

15 The upper end plate 29 at the top is a substantial duplicate of the end plate 28 at the bottom. This ring 29 includes a thickened part 41 carrying a cylindrical wall 42 which is spaced from the column 25 and which provides a recess 20 which receives a bearing assembly 43 and a sealing ring 44. A nut 45 carries a flange 46 which closes this recess and retains the ring 44 and bearing assembly 43 in assembled relation. This upper end plate 29 also carries a thinner peripheral portion 47 which is secured to the intermediate ring 30 by screw bolts shown at 75.

25 A packing gland 48 is positioned about the column 25 at the top and is engaged by the outer spring 40. This gland carries another sealing ring 49 which is engaged by the spring 39, the sealing ring being a substantial duplicate of that at the lower end of the column.

30 A sheave is referred to in its entirety by the reference character S and includes an inner hub structure of sheet metal parts 50 and 51. It will be noted that the sheave part 50 is secured to the intermediate ring 30 by screw bolts shown at 52. The lower sheave part 51 is secured in a similar manner to the ring 30 by headed screw bolts corresponding to screw bolts 52. The sheave S also includes a web structure at 53 which extends outwardly to the peripheral part formed with a groove 54 which actually receives the hose H.

35 40 It will be noted that the sheave S may be made of complementary halves which are substantial duplicates. Thus the upper half carries the part 50 and web 53 while the lower half carries the part 51 and the other web 53. These two halves together define the groove 54 at the outer periphery.

45 A spring housing is made up of two L-shaped members 55 and 56. The member 55 is anchored to the hub by one of the screw bolts 75, as shown in Figure 6, while the housing part 56 is anchored to the pedestal 19. A spiral spring 57 is received within the spring housing, one end of this spring being anchored to the housing part 55 and the other end to the housing part 56. The 50 normal tendency of the spring 57 is to retain the hub X in the position shown in Figure 4 in which the hose H is fully taken up on the sheave S to the maximum extent possible. When the hose is withdrawn into an extended position, the 55 sheave S is rotated against the influence of the spring 57 so that when the extending tension is relieved the spring will return the hose to its normally wound position.

60 Referring now more particularly to Figure 7, 50 it will be noted that one end of the hose H is anchored to the ring 30 as shown at 58. This connection may be achieved by having the end of the hose threaded and screwing it into a threaded socket. It is evident that gasoline under 65 pressure may come through the conduit 24,

through the coupling 23, passageway 22, through the recess 21, and up through the column 25, whence it passes out the ports 27 into the space enclosed by the ring 30. The hose H is connected to this ring 30 at 58 and hence the communication to the hose is established. This communication remains in effect regardless how the hub X may be rotated or to what position it may assume.

Carried by the uprights 16, cross bar 17, and table 18 at appropriate points are a plurality of guide rollers 59 which are disposed opposite to the peripheral groove 54 of the sheave S. These guide rollers serve to maintain the hose H in position in this groove. Each of the guide rollers 59 is mounted on a stud which may take the form of a headed bolt 60.

The casing C adjacent to the top is formed with a recess 61 around which is disposed a spout 62. This spout 62 carries a plurality of guide rollers 63 which may be arranged both horizontally and vertically as shown in Figures 4 and 5. The hose H passes between these guide rollers. The casing C inside the opening 61 may also carry a bracket 64 which in turn carries a plurality of guide rollers 65 which also aid in properly positioning the hose H.

Operation

While the operation of the above mechanism is believed to be obvious, it may be briefly outlined by noting that the driver of the car A may park at any place within a fairly wide range from the pump P. With the car so stopped, the attendant grasps the nozzle 13 of the hose H and inserts it into the inlet 12. In so positioning the nozzle, it may be necessary to extend the hose H. This may be done simply by applying sufficient tension on the hose to cause the sheave S to unwind against the influence of the spring 51. In so unwinding the hose pays out between the guide rollers 65 and 63. The pump mechanism proper is now started in operation to pump gasoline through the line 24, passageway 22, column 25, openings 27, to the connection at 58 where it passes through the hose H.

After the tank of the car A has been filled, the operator simply withdraws the discharge nozzle 13 and in straightening the hose substantially opposite to the spout 62, the tension is relieved so that the spring 51 is rendered effective to rotate the sheave S in the opposite direction and wind a portion of the hose H thereon.

It will be noted that under ordinary conditions any sharp bend on the part of the hose H will be just adjacent to the spout 62 and will create sufficient resistance to prevent the spring 51 from winding up the hose.

While a preferred specific embodiment of the invention is hereinbefore set forth, it is to be clearly understood that the invention is not to be limited to the exact mechanisms illustrated and described because various modifications of these details may be provided in putting the invention into practice within the purview of the appended claims.

What is claimed is:

1. In a reel assembly for a gasoline dispensing pump, a tubular column having an internal chamber therein for receiving liquid under pressure and including port means in the side wall of said column, a hub assembly journaled on said column, said hub assembly consisting of a pair of spaced end plates and a ring interposed between and engaged by and spacing said end

plates, said end plates providing journal means for said hub assembly, and said end plates and said ring defining a chamber around said column at the level of said ports therein to receive liquid under pressure, a running seal member disposed between each of said end plates and said column within said chamber to prevent escape of liquid under pressure from said chamber, an opening in said ring forming an outlet passage for flow of liquid from said chamber, and a reel sheave secured to said ring to receive a gasoline dispensing hose.

2. In a reel assembly for a gasoline dispensing pump, a tubular column having an internal chamber therein for receiving liquid under pressure and including port means in the side wall of said column, a hub assembly journaled on said column, said hub assembly consisting of a pair of spaced end plates and a ring interposed between and engaged by and spacing said end plates, said end plates providing journal means for said hub assembly, and said end plates and said ring defining a chamber around said column at the level of said ports therein to receive liquid under pressure, means forming a sealing face on each of said end plates within said chamber and encircling said column, running seal members on said column engaging said sealing faces, compression spring means around said column and engaging the seal members urging said sealing members against said sealing faces to prevent escape of liquid from said chamber, an opening in said ring forming an outlet passage for flow of liquid from said chamber, and a reel sheave secured to said ring to receive a gasoline dispensing hose.

3. In a reel assembly for a gasoline dispensing pump, a tubular column having an internal chamber therein for receiving liquid under pressure and including port means in the side wall of said column, a hub assembly journaled on said column, said hub assembly consisting of a pair of spaced end plates and a ring interposed between and engaged by and spacing said end plates, said end plates providing journal means for said hub assembly, and said end plates and said ring defining a chamber around said column at the level of said ports therein to receive liquid under pressure, means forming a sealing face on each of said end plates within said chamber and encircling said column, running seal members on said column engaging said sealing faces, a single compression spring around said column and extending between said sealing members urging said sealing members against said sealing faces to prevent escape of liquid from said chamber, an opening in said ring forming an outlet passage for flow of liquid from said chamber, and a reel sheave secured to said ring to receive a gasoline dispensing hose.

H. HIX WOLFE.
